UNITED STATES PATENT OFFICE.

CHARLES F. STODDARD, OF BOSTON, MASSACHUSETTS.

AUTOMATIC MUSICAL INSTRUMENT.

1,262,279.

Specification of Letters Patent.

Patented Apr. 9, 1918.

Application filed March 5, 1913. Serial No. 752,127.

To all whom it may concern:

Be it known that I, CHARLES F. STODDARD, a citizen of the United States, and a resident of Boston, county of Suffolk, and 5 State of Massachusetts, have invented an Improvement in Automatic Musical Instruments, of which the following description, in connection with the accompanying drawings, is a specification, like characters on 10 the drawings representing like parts.

This invention relates to an apparatus for automatically operating a hammer-rail of a piano action for the purpose of regulating or controlling the intensities. Among 15 other objects the invention is intended to provide an apparatus susceptible of being controlled through the note sheet for operating a preferably flexible hammer-rail, as by having different portions of the hammer- 20 rail differently operated to produce varied effects in different parts of the scale.

In the drawings:

Figure 1 is a diagrammatic representation of a hammer and hammer-rail, together 25 with automatic controlling mechanism embodying the invention;

Fig. 2 is a plan view of the piano action showing one practicable form of flexible rail and operating means therefor;

30 Fig. 3 represents a fragment of a note sheet having marginal perforations to co-operate with the tracker shown in Fig. 1;

Fig. 4 is a detail on an enlarged scale 35 of the constrictions provided in the ducts leading from the bellows to their valve chambers.

In Fig. 1 a conventional hammer 1 is shown mounted on its pivoted butt 2. Such part of the hammer-rail as pertains to the 40 illustrated hammer is represented in section at 3 and is shown as being carried upon the movable board 4 of the double acting pneumatic which comprises the bellows 5 and bellows 6. These two bellows, 5 and 6, have 45 no inter-communication in the illustrative form shown in the drawings.

A duct 7 leads from the bellows 5 to a chamber 9 which contains a double-acting valve 10 which opens the chamber 9 alternately 50 to atmosphere and the exhaust of chamber 11. The valve 10 is controlled by the diaphragm of a chamber 12 which has a duct 13 leading to a tracker vent 14. The parts just described as associated with the 55 bellows 5 are duplicated for the bellows 6; they comprise the duct 15, chamber 17, valve

18, diaphragm chamber 19, duct 20 and tracker vent 21.

In order to provide a comparatively slow collapsing movement of the bellows, some 60 means of constricting the exhaust or admission of atmosphere is provided. For example, the duct 7 has a constriction 8 and the duct 15 has a constriction 16. Any other suitable arrangement for the purpose 65 may be employed as will be understood by those skilled in the art.

It will be evident that when one of the bellows 5 or 6 is exhausted the movable board 4 and connected hammer-rail section 70 3 will be moved in such manner as to change the distance between the appropriate hammers and their strings which is indicated diagrammatically at 22.

In order to hold the hammer-rail 3 in its 75 various positions of adjustment, it may be provided with any practicable form of stop or check mechanism, as for example by having a friction brake 23 located against the edge of the movable board 4. The frictional engagement between these parts is such as to hold the movable board 4 and hammer-rail 3 firmly in position until it is intentionally moved in the operation of one or the other of the bellows 5 and 6. 80 85

Referring now to Fig. 3 a row of perforations 25 is arranged to co-operate with the tracker vent 14 of Fig. 1, and a second row of perforations 26 is arranged to co-operate with the tracker vent 21. So long 90 as the vent 14 remains open the exhaust in the chamber 11 continues in communication with the bellows 5 thereby collapsing the latter at the comparatively slow rate of speed determined by the constriction 8 in 95 the duct 7. In this way the hammer-rail 3 may be moved progressively nearer to the strings to diminish the intensity of the playing; and the length of a perforation in the note sheet will determine the duration of 100 the collapsing movement of the bellows 5 and thereby will determine the approach of the hammer-rail to the strings. The arrangement of the constriction is such that the opening of the vent 14 by the passage of 105 a single circular perforation in the note sheet, collapses the bellows 5 through only a fraction of its throw. Hence from its position most remote from the strings, the hammer-rail may be moved toward the 110 strings through a fraction of its throw controlled by a single circular perforation or

through its entire throw to the position of nearest approach to the strings by a longer perforation such as is necessary to entirely collapse the bellows 5. When the tracker vent 14 is closed following the passage of a perforation, the bellows 5 is promptly thrown into communication with atmosphere by the valve 10 but the co-operation of the friction brake 23 with the movable board 24 holds the parts in whatever position they had been adjusted to by the last perforation.

The opening of the vent 21 by perforations in the note sheet serves in like manner to collapse the bellows 6 thereby to move the hammer rail toward the left in Fig. 1 and to move the hammers farther from the strings.

Thus the bellows 5, or its equivalent, serves the purpose of producing diminuendos, or of diminishing intensities by a series of substantial steps when desired; and the bellows 6 serves the reverse purpose of causing crescendos, or of increasing intensities by substantially distinct steps. For convenient reference hereafter, the bellows 5 may be referred to as the diminuendo bellows; and the bellows 6 may be referred to as the crescendo bellows.

Referring to Fig. 3 the perforation 30 is intended to open the vent 14 for a sufficiently long period to allow for a maximum collapse of the bellows 5 to produce a continuous diminuendo indicated graphically by the plotted line 31 which extends from the fortissimo line to the pianissimo line. The perforation 32 is intended to open the vent 21 for a sufficiently long period to collapse the bellows 6 through its maximum throw to produce a continuous crescendo indicated by the line 33. The following diminuendo perforations 34 open the vent 14 intermittently and produce a series of diminuendo steps indicated by the line 35, similarly the group of perforations 36 produces an intermittent crescendo indicated by the line 37. Another continuous diminuendo is produced by the perforation 38 as indicated by the line 39. Thereafter, there is no perforation for a space on the note sheet and the hammer-rail remains in the position to which it was previously adjusted by the perforation 38, being held so adjusted by the brake 23; hence the playing remains at an uniform intensity as indicated by the line 40, until a single crescendo perforation 41 produces a crescendo step indicated by the line 42. Further crescendo steps are produced by the perforations 45 and 46, as indicated by the lines 47 and 48.

Referring now to Fig. 2, a plan view of a specific flexible hammer-rail is therein indicated associated with the strings 22 and hammers 1, 1, the rail 3 being divided into two or more parts 3^a and 3^b, jointed or otherwise rendered flexible. Three sets of cre-

scendo and diminuendo bellows 5 and 6 may be employed with such a hammer-rail, one set controlling the hammer-rail at the point 50, another at the point 51, and a third at the point 52. Each of these sets may be operated independently of the others by means of its own two rows of perforations in the music sheet, so that the hammer-rail sections may be moved separately or together into various positions as will be readily understood by those skilled in the art. Each of the three sets of crescendo and diminuendo bellows may have its corresponding two rows of perforations in the music sheet but these are unnecessary to be illustrated.

The foregoing will suffice to indicate to those skilled in the art the various modifications to which the specific illustrative embodiment of the invention is susceptible. It is to be understood that the invention is not limited to the specific details of construction, organization, and mode of operation which have been described.

Claims:

1. In an automatic musical instrument, the combination with a series of hammers, of a hammer rest rail, and automatic expression varying means for shifting the position of said hammer rest rail by substantially continuous progression, thereby varying by substantially continuous progression the length of stroke of the hammers.

2. In an automatic musical instrument, the combination with a series of hammers, of a hammer rest rail, automatic means for shifting the position of said hammer rest rail by substantially continuous progression, thereby varying by substantially continuous progression the length of stroke of the hammers, a tracker, and means connected with the tracker for controlling said shifting means.

3. In an automatic musical instrument, the combination with a series of hammers, of a hammer rest rail, and automatic expression varying means operatively connected to said hammer rest rail for shifting the position thereof by substantially continuous progression or by predetermined increments, thereby varying the length of the stroke of said hammers by substantially continuous progression or by predetermined increments.

4. In an automatic musical instrument, the combination with a series of hammers, of a hammer rest rail, automatic expression varying means operatively connected to said hammer rest rail for shifting the position thereof by substantially continuous progression or by predetermined increments, thereby varying the length of the stroke of said hammers by substantially continuous progression or by predetermined increments, a tracker, and means connected with the tracker for controlling said shifting means.

5. In an automatic musical instrument, the

combination with a series of hammers, of a flexible hammer rest rail, and a plurality of automatic means operatively connected to said hammer rest rail at a plurality of points 5 for shifting by substantially continuous progression the position of rest of successive hammers, whereby the length of stroke of the successive hammers varies by substantially continuous progression from end to end of said series.

6. In an automatic musical instrument, the combination with a series of hammers, of a flexible hammer rest rail, a plurality of automatic means operatively connected to said 15 hammer rest rail at a plurality of points for shifting by substantially continuous progression the position of rest of successive hammers, whereby the length of stroke of the successive hammers varies by substantially continuous progression from end to end of said series, a tracker, and means connected with the tracker for controlling said shifting means.

7. In an automatic musical instrument, the 25 combination of a series of hammers, of a flexible hammer rest rail, and a plurality of automatic means connected to said flexible hammer rail at a plurality of points for shifting by substantially continuous progression or by predetermined increments the 30 position of rest of successive hammers, whereby the length of stroke of successive hammers varies by substantially continuous progression or by predetermined increments 35 from end to end of said series.

8. In an automatic musical instrument, the combination with a series of hammers, of a flexible hammer rail, a plurality of automatic means connected to said flexible hammer rail at a plurality of points for shifting by substantially continuous progression or by predetermined increments the position of 40 rest of successive hammers, whereby the length of stroke of successive hammers varies from end to end of said series, a tracker, and means connected with the tracker for controlling said shifting means.

9. In an automatic musical instrument, the combination with a series of hammers, of a 50 hammer rest rail, pneumatic means operatively connected to said hammer rest rail for shifting the position of rest thereof, a tracker, valve means interposed between said pneumatic shifting means and said tracker 55 to govern the exhaust of air from said pneumatic means, a note sheet to control the operation of said valve means provided with perforations to govern exhaust of air from

said pneumatic means intermittently or by substantially continuous progression. 60

10. In an automatic musical instrument, the combination with a series of hammers, of automatic expression varying means for shifting by substantially continuous progression the position of rest thereof by varying 65 the length of stroke of the successive hammers varies from end to end of said series.

11. In an automatic musical instrument, the combination with a series of hammers, of means for shifting by substantially continuous progression the position of rest thereof, whereby the length of stroke of the successive hammers varies from end to end of said series, a tracker, and means connected with the tracker for controlling said shifting means. 75

12. In an automatic musical instrument, the combination of a hammer rail; automatically operated means for moving said 80 hammer rail by substantially continuous progression in one direction, similar means for moving said hammer rail by substantially continuous progression in the opposite direction, and means for controlling 85 said automatically operated means.

13. In an automatic musical instrument, the combination of a flexible hammer rail, a plurality of automatic means for differently moving different parts of said rail by substantially continuous progression in one direction, a plurality of automatic means for differently moving different parts of said 90 hammer rail by substantially continuous progression in the opposite direction, and means for controlling said automatic means. 95

14. In an automatic musical instrument, the combination of a flexible hammer rail, a plurality of automatic means for differently moving different parts of said rail by substantially continuous progression in one direction, a plurality of automatic means for differently moving different parts of said 100 hammer rail by substantially continuous progression in the opposite direction, means for controlling said automatic means, a tracker, and means connected with the tracker for controlling 105 said automatic means.

In testimony whereof, I have signed my name to this specification, in the presence of 110 two subscribing witnesses.
